M. L. JOHNSTON,
GUN BARREL MUZZLE STEADIER,
APPLICATION FILED SEPT. 21, 1918.

Patented Sept. 13, 1921.

INVENTOR.
MILLARD L. JOHNSTON

BY

Thomas L. Wilder

ATTORNEY.

UNITED STATES PATENT OFFICE.

MILLARD L. JOHNSTON, OF UTICA, NEW YORK.

GUN-BARREL-MUZZLE STEADIER.

1,390,447.

Specification of Letters Patent. Patented Sept. 13, 1921.

Application filed September 21, 1918. Serial No. 255,165.

To all whom it may concern:

Be it known that I, MILLARD L. JOHNSTON, a citizen of the United States, residing at Utica, in the county of Oneida and State of

5 New York, have invented certain new and useful Improvements in Gun-Barrel-Muzzle Steadiers, of which the following is a specification, reference being had therein to the accompanying drawing.

10 My invention relates to a gun barrel muzzle steadier, and I declare the following to be a full, clear, concise and exact description thereof sufficient to enable anyone skilled in the art to which it appertains to make and 15 use the same, reference being had to the accompanying drawings in which like reference characters refer to like parts throughout the specifications.

The object of the invention is to provide 20 a device that will prevent the jumping of the muzzle upon the discharge of the gun. This result is highly desirable in view of the fact that especially in all high powered rifles, the muzzle of the gun will give a sudden jump 25 upward immediately the gun is fired. This motion of the muzzle disturbs the aim of the shooter and causes flinching. Moreover, it is directly responsible for inaccuracy of shooting straight. The device here mentioned is 30 intended to correct this evil.

The object will be understood by referring to the drawings in which:

Figure 1 is a perspective view of a firearm, showing the muzzle steadier attached 35 thereto;

Fig. 2 is an enlarged detail view, showing a vertical section of the muzzle steadier connected to the gun;

Fig. 3 is an enlarged perspective view of 40 the muzzle steadier;

Fig. 4 is a detail enlarged view of an adjustable nut employed;

Fig. 5 is an enlarged view of a front sight, showing certain parts in section, that may 45 be connected to the muzzle steadier.

Referring more particularly to the drawings, the device embodies a cup shaped member —1— which has formed integral therewith and at right angles thereto an elbow 2.

50 The elbow 2 has a central recess and is equipped on its inner surface with left handed threads 3 for attaching the device to the muzzle 4 of a barrel 5 of the firearm 6. The inner surface of the elbow 2 is threaded also 55 with right hand threads 7 for mounting the adjustable nut 8 provided with a counter

sunk recess 9 for the insertion of the end of a suitable tool.

The adjustable nut 8 is adapted to be turned upon its threads 7 to such a location 60 that its surface will abut against the end surface of the muzzle 4 when the elbow 2 has been turned upon the threads 3 and come to rest in set position with the chamber 10 of the cup shaped member —1— depending and 65 at the correct angle to the bore 11 of the barrel 5.

The lower surface of the cup shaped member —1— is closed by the screw threaded head 12 that is provided with a counter 70 sunk slot 13 for the insertion of the end of a suitable tool. The removal of the head 12 will give access to the interior of the chamber 10 for cleaning purposes.

The cup shaped member —1— has a long 75 narrow slot 14 the lower end of which is rounded out at 16 to form an opening concentric with the bore 11 of the barrel 5 and is somewhat enlarged to permit the passage of a bullet projected from the barrel 5. The 80 slot 14 extends upwardly and along the top surface of the member —1— for a short distance.

When the gun is discharged, a part of the gases of explosion will expand into the 85 chamber 10 of the cup shaped member —1— and, thereby, exert a pressure downward which pressure will counteract the tendency of the muzzle 4 of the barrel 5 to fly upward.

A novel front sight such as hereinafter 90 described may be attached to the muzzle steadier. For this purpose, the top surface of the elbow 2 is equipped with a hollow boss 20 having an internal screw thread aperture for the insertion of the screw bolt 21. The low- 95 ermost surface of the bolt 21 rests, when seated, in an aperture 22 formed in the barrel 5 of the firearm 6, whereby to aid in holding the muzzle steadier in proper relation to the barrel 5 of the firearm 6. The upper end of the screw bolt 21 has formed integral therewith a ring 23 with a central orifice 24 for the insertion of the end of a cartridge which is adapted to be used to turn the bolt 21 home into the aperture of the boss 20. 100 Arms 25—25 extend upward from the ring 23 and are provided with yielding free ends having teeth 26—26 which fit into a correspondingly formed annular groove in the shaft 27. The lower part 28 of the shaft 27 105 is corrugated with longitudinal ribs adapted to fit into suitable fissures formed on the in-

inner surface of the arms 25, whereby the shaft 27 can be held at any given angle to which it may be turned within the arms 25. Furthermore, the shaft 27 is bent at an angle to the vertical at 29 and again at 30 to form an offset portion. The upper end of the shaft 27 is tapered and has attached a ball or sphere 31 which provides a front sight for the gun. The sphere 31 is located in the center of a ring 32 having a boss 33 with an aperture extending therethrough and through the ring 32 for the projection of the upper end of the shaft 27 upon which it is mounted to turn. The boss is split and equipped with free yielding ends having teeth 35-35 that engage an annular groove 36 in the shaft 27, whereby to hold the ring 32 in vertical position.

The offset portion of the shaft 27 permits the adjustment of the front sight 31 within the range of positions indicated by the full and dotted lines in Fig. 5.

The top surface of the arms 25 may be equipped with a graduated scale to denote the desired degree of arc through which the shaft 27 is turned to effect a given alinement with respect to the rear sight.

Having thus described my invention what I claim as new and desire to secure by Letters Patent is:

1. In a gun barrel muzzle steadier, continuous walled depending means connected with the muzzle of said barrel, said means having a chamber and a vent above said chamber whereby the tendency of the muzzle to jump upward is counteracted.

2. In a gun barrel muzzle steadier, a continuous walled depending gas chamber attached to the muzzle of said barrel, said chamber having a vent above the chamber whereby the tendency of the muzzle to jump upward upon the discharge of the gun is counteracted.

3. In a gun barrel muzzle steadier, a continuous walled depending cup shaped member having an elbow containing a gas chamber with vent above said chamber, means for attaching said cup shaped member to the muzzle of the gun, whereby the tendency of the muzzle to jump upward upon the discharge of the gun is counteracted.

4. In a gun barrel muzzle steadier, a continuous walled depending cup shaped member attached to the muzzle of the gun, a chamber in said cup shaped member adjustable in depth, whereby the tendency of the muzzle to jump upward upon the discharge of the gun is counteracted, and an opening for the escape of the gases of explosion that enter said chamber.

5. In a gun barrel muzzle steadier, a cup shaped member attached to the muzzle of the gun, an elbow having a recess equipped with screw threads, whereby to attach said device to the muzzle of the gun, a nut for

determining the position of the cup shaped member relative to the muzzle, and a slot in said cup shaped member, whereby to permit the gases of explosion to escape from said chamber.

6. In a gun barrel muzzle steadier, a continuous walled depending cup shaped member attached to the muzzle of the gun, an elbow having a recess with screw threads for mounting said cup shaped member to the muzzle of the gun, a slot in said cup shaped member for permitting the gases of explosion to escape, and a movable head adapted to be wholly withdrawn from said cup shaped member, whereby to give access to the interior thereof for cleaning purposes.

7. In a gun barrel muzzle steadier, a depending cup shaped member adapted to counteract the tendency of the muzzle to jump upward, an elbow having a recess with screw threads, whereby to attach the cup shaped member to the muzzle, and a sight attached to said elbow, and means for turning and holding said sight at any desired angle.

8. In a gun barrel muzzle steadier, means adapted to be attached to and depend from said barrel, said means including a continuous walled depending chamber in communication with the bore of said barrel, said means adapted to receive, deflect and discharge at right angles upwardly into the atmosphere a portion of the forces exerted initially within the gun barrel against the projectile.

9. In a gun steadyng device a continuous walled depending chamber, a vent above said chamber, a projectile outlet and means for attaching said device to the gun barrel so as to place the bore thereof in communication with the chamber.

10. In a device for steadyng the muzzle of a gun barrel at the moment of firing an explosive projectile, a continuous walled depending chamber adapted to be in communication with the bore of said barrel and to receive, deflect and discharge at right angles upwardly a portion of the explosive gases traveling outwardly through said barrel, and means for attaching said device to said barrel.

11. In a device for steadyng a gun when fired, a continuous walled depending chamber, a vent opposite said chamber, an outlet for a projectile and means for attaching the device to the gun.

12. In a gun barrel muzzle steadier a continuous walled depending gas chamber adapted to receive a portion of the explosive gases and deflect same upwardly through a vent opposite said chamber whereby the tendency of the muzzle to jump upwardly is counteracted.

13. The combination of a gun barrel adapted to fire explosive projectiles and a

- device for steadyng the muzzle thereof, said device including a continuous walled depending chamber in communication with the bore of said barrel, said means being adapt-
5 ed to receive, deflect and discharge upwardly at right angles to said bore a portion of the explosive gases, whereby the tendency for said muzzle to jump upward is nullified and counteracted.
- 10 14. In a device for steadyng and counteracting the upward jump of the muzzle of a gun at the moment of firing, a continuous walled depending chamber communicating with the bore of the gun barrel and adapt-
15 ed to receive therefrom a portion of the explosive gases, a vent above said chamber, an outlet for a projectile, and means for attaching said device to said gun barrel.
15. The combination of a gun barrel
20 adapted to fire explosive projectiles and a device adapted to steady the muzzle of said barrel at the moment of firing, said device being adapted to be attached to said barrel and including continuous walled depending
25 means whereby a portion of the explosive gases are received and deflected downwardly and subsequently discharged upwardly into the atmosphere at right angles to their initial direction of travel in said bore.
- 30 16. The combination of a gun barrel adapted to fire an explosive projectile and a device adapted to steady the muzzle of said barrel at the moment of firing, said device being adapted to be attached to said barrel,
35 said device having a continuous walled chamber depending from said barrel and communicating with the bore thereof, said chamber being adapted to receive a portion of the explosive gases within said bore and
40 deflect same downwardly, said means being further adapted to subsequently discharge said gases upwardly into the atmosphere at right angles to their initial direction of travel when within said bore.
17. A device adapted to be attached to the 45 barrel of an explosive projectile gun, said device having openings registering with the bore of said barrel, said device having a continuous walled depending chamber communicating with said bore through said openings, 50 said chamber adapted to receive a portion of the explosive gases in their outward travel through said bore and to deflect said gases downwardly to be subsequently discharged through a vent in said chamber, 55 said vent being above the axis of said bore and above said chamber.
18. In an explosive firearm having a barrel, a muzzle steadier device adapted to be attached to the end of said barrel, said device including a continuous walled depending chamber and in communication with the bore of said barrel, an opening in said chamber in register with the bore of said barrel, and an opening in the top wall of said de- 60 pending chamber. 65
19. In an explosive firearm having a barrel, a muzzle steadier device adapted to be attached to the end of said barrel, said device including a continuous walled de- 70 pending chamber and in communication with the bore of said barrel, an opening in said chamber in register with the bore of said barrel, an opening in the top wall of said depending chamber, and means for locking said device in a fixed position on said barrel. 75

In testimony whereof I have affixed my signature.

MILLARD L. JOHNSTON.
